RECORD MAKING MACHINE

Oscar J. Sundstrand, West Hartford, Conn., assignor to Underwood Elliott Fisher Company, New York, N. Y., a corporation of Delaware

Application December 30, 1939, Serial No. 311,742

20 Claims. (Cl. 197—66)

This invention relates to typewriters and other record making machines and more particularly to a power operated carriage return mechanism for such machines.

One object of the present invention is to improve the construction and mode of operation of power operated carriage return mechanisms for record making machines and to produce a novel and improved mechanism by which the carriage of such a machine may be selectively returned by power to any one of two or more returned positions.

Another object of the invention is to produce, for machines of the above class, a carriage return mechanism for causing the return of the carriage by power to any one of two or more returned positions, having stopping devices for stopping the carriage selectively in the desired position and retaining means for holding the stopping devices in stopping position during the return of the carriage in which novel and improved mechanism is provided for releasing said retaining means to allow the stopping devices to return to normal positions.

With the above and other objects in view, the invention consists in a carriage return mechanism embodying the novel and improved features, constructions and combinations of parts hereinafter described and particularly pointed out in the claims, the advantages of which will be readily understood and appreciated by those skilled in the art.

In the present construction, the retaining means for holding the stopping devices in stopping position, during the carriage return movement, is arranged to be released by various operating mechanisms which may be selectively actuated at the beginning of the next operation of the machine following the return of the carriage. The machine disclosed in this application is provided with mechanisms for releasing the holding or retaining means respectively upon the actuation of a type key lever, the column tabulator key lever, any one of the decimal tabulator key levers, the release key lever or the space bar. The machine is provided also with mechanism for releasing the stop retaining means upon the actuation of the line space brake release lever.

The invention will be clearly understood from the accompanying drawings illustrating the invention in its preferred form and the following detailed description of the constructions therein shown.

In the drawings:

Fig. 1 is a perspective view illustrating certain

parts of a typewriting machine of the Elliott Fisher type embodying the invention.

Fig. 2 is a view in side elevation partly in section illustrating the key carriage, the carriage return mechanism and certain devices for controlling said mechanism and the stopping of the return movement of the carriage.

Fig. 3 is a detail plan view, partly broken away, of the key carriage of the machine and illustrating particularly the mechanisms for releasing the holding or retaining means for holding the carriage stopping devices in stopping position during the return movement of the carriage.

Fig. 4 is a detail view in vertical section illustrating certain parts of the mechanisms shown in Fig. 3, and certain additional mechanism.

Fig. 5 is a detail view in front elevation of a portion of the key carriage and certain associated parts and showing particularly the mechanism for holding the carriage stopping devices in position during the return of the carriage.

Fig. 6 is a view similar to Fig. 5, showing certain of the parts in different positions.

Fig. 7 is a detail view in side elevation illustrating a portion of the mechanism shown in Fig. 2, with certain of the parts in different positions.

Fig. 8 is a view in side elevation, with parts in section, illustrating the key carriage and certain devices for controlling the carriage return mechanism and the stopping of return movement of the carriage of a machine embodying a modified form of the invention.

Fig. 9 is a detail plan view partly broken away and partly in section illustrating a portion of the mechanism shown in Fig. 8, and

Fig. 10 is a view similar to Fig. 8, illustrating a portion of the mechanism shown in Fig. 8, with certain of the parts in different positions.

The invention is illustrated in this application as embodied in a machine having the same general construction, arrangement and mode of operation of parts as the machine disclosed in the patent to Foothorap, No. 1,904,127, dated April 18, 1933.

Except for the mechanisms for releasing the retaining or holding means for holding the stopping devices for stopping the return of the carriage, the various mechanisms of the machine shown in Figs. 1 to 7, inclusive, of the drawings have substantially the same construction, arrangement and mode of operation as the corresponding mechanisms illustrated and described in applicant's pending application Serial No. 248,553, filed December 30, 1938, upon which

Patent No. 2,286,318, dated June 16, 1942, has been granted.

Referring to the drawings, a flat platen 1 is mounted in a platen frame comprising a pair of parallel side bars or rails 2 suitably supported on a standard, not shown. A portion of each bar is toothed to form a rack engageable by traction gears 4 fast on a shaft 6 extending transversely of the side bars and supported by bearings in brackets, one of which is shown at 8, projecting upwardly from the rear side members of the rectangular line space frame 10. This shaft also carries wheels 9a engaging tracks 9 formed on the side bars 2 and the front rail 12 of the line space frame 10. The rear side members of the line space frame 10 are likewise supported by wheels, (not shown) engaging said tracks to enable the line space frame 10 readily to move forwardly and rearwardly along said tracks.

The rear and front cross rails 11 and 12 support a key carriage 14 shown in dot and dash lines in Fig. 1 for travel across the platen 1 in letter spacing direction and return, on front and rear wheels 15.

The key carriage contains the customary key actions, ribbon mechanism and controls for the carriage escapement, not necessary to illustrate, but disclosed in the U. S. patent to Foothorap No. 1,203,519, dated October 31, 1916. The usual spring barrel 16 is mounted on the line space frame 10, a tape 18 connecting the spring barrel with the key carriage 14 to draw the carriage toward the right in letter spacing direction under control of the escapement mechanism.

Power drive

The key carriage 14 may be manually returned to the left hand margin from any point to which it has been advanced in letter spacing direction, but to relieve the operator of the work of returning the carriage, a motor 20 is provided, conveniently mounted on a casting, (not shown) secured to and projecting rearwardly from the rear rail 11 of the line space frame 10 with which it travels.

Referring to Figure 2 of the drawings, power from the motor is taken from the worm 22 fast on the motor shaft 24 and meshing with a worm gear 26 having a friction clutch connection 28 with a counter shaft 30 journaled in the casting and extending forwardly beneath a carriage return rack 31 secured to the flanged rear end of an apron 32 projecting from the deck 34 of the key carriage 14.

A wide carriage return pinion 36 journaled on the forward end of the counter shaft 30 and axially movable along the shaft, meshes with the teeth of the carriage return rack 31 at all times, the return pinion having a peripherally grooved collar 38 terminating at its rear end in a driven clutch member 40 normally disengaged from a driving clutch member 42 fast on the counter shaft.

The free end of a clutch shift finger 44 lies in the groove in the sliding rotatable collar 38, the finger being secured to a clutch shifting shaft 46 journaled in the motor support casting. A clutch shifting arm 48 fast on one end of the clutch shifting shaft 46 is provided with a lateral locking lip 50 normally engaged by a locking latch 52 journaled on a trip shaft 54 extending across the machine and supported in bearings projecting from the back of the rear rail 11 of the line space frame. A fan-shaped trip arm 56 secured to the trip shaft 54 extends rearwardly between two studs 58 and 60 projecting respectively from the

hooked latch 52 and from the clutch shifting arm 48, a normally tensioned spring 62 connecting the two studs to form a yielding link therebetween and normally maintaining the hooked latch 52 engaged with the clutch shifting arm 48 to retain the clutch members 40 and 42 disengaged.

Control of automatic carriage return mechanism

Curved arms 55 projecting upwardly and forwardly from the trip shaft support a tripping bail 64 toothed at its opposite ends and rocking with the shaft 54. Mounted on the right hand end of the tripping bail is a cam block 66 arranged to be engaged by a roll 68 projecting downwardly from the carriage apron.

In the normal positions of the parts, the hooked latch 52 is engaged with the lip 50 of the clutch shifting arm 48, and the trip shaft 54 is retained in its limiting counterclockwise position, Fig. 2, and the tripping bail 64 is retained in its rearmost position by the action of the spring 62. As the carriage 14, travelling in letter spacing direction, advances the printing point toward the extreme right hand margin of the work sheet, the roll 68 wipes across the inclined face of the cam block 66 and rocks the bail forwardly, thereby rocking the trip shaft 54 in a clockwise direction, Fig. 2.

The rearwardly projecting trip arm 56 is swung upwardly by the rocking movement of the trip shaft to disengage the hooked latch 52 from the clutch shifting arm 48 and, in so doing, additionally tensions the spring 62, which spring, acting as a tensile link, rocks the clutch shifting shaft 46 and its clutch shifting finger 44 counterclockwise, Fig. 2, to slide the driven member 40 of the carriage return clutch along the counter shaft 30 into engagement with the driving member 42, the carriage return pinion 36 being of sufficient width to maintain its engagement with the carriage return rack throughout the clutch shifting action.

The motor 20 is preferably of the constantly running type and will then drive the carriage in contra-letter spacing direction toward the left hand side of the machine. As the carriage approaches the end of its return movement under the influence of the motor 20, the tripping bail 64 is swung back rearwardly to its normal position. During this operation, the tripping arm 56 is pressed against the stud 60 on the clutch shifting arm 48 and rocks the arm, together with the clutch shifting shaft 46 and clutch finger 44 in a clockwise direction, Fig. 2, to cause the finger to disengage the driven clutch member 40 from the driving clutch member 42 thereby disconnecting the motor 20 from the travelling carriage 14.

The spring 62 tends to draw the hooked latch 52 downwardly, as the clutch shifting arm 56 is swung downwardly and when the arm 48 reaches a certain position, the latch snaps down over the lip 50 on said arm to lock the clutch shift mechanism, and hence the clutch members, in disengaged positions.

All of the mechanisms above described have substantially the same construction arrangement and mode of operation as the corresponding mechanisms of the machine illustrated and described in applicant's pending application Serial No. 149,571, filed June 22, 1937, except that a continuously running motor is employed in the present machine and the switch and control mechanism for closing the motor circuit upon

throwing in the carriage return mechanism and for opening the motor circuit upon throwing out the carriage return mechanism are omitted.

The mechanism for swinging the tripping bail 64 rearwardly as the carriage approaches the end of its return movement will be hereinafter described.

Partial carriage return

The present machine is provided not only with mechanism for automatically returning the carriage to position to begin the typing of a line, but is also provided with mechanism for stopping the carriage in fully returned position or in either of two partial return positions at different distances to the right of its fully returned position. In carrying out the invention, three carriage return keys are mounted on the key carriage 14 in place of the single carriage return key shown and described in Foothorap Patent No. 1,904,127. By the respective actuation of these keys the carriage return mechanism will be thrown into operation and the return movement of the carriage will be caused to be arrested with the carriage in any one of three different return positions, the stop position being selected by the actuation of the appropriate key.

Referring to Figs. 1, 2 and 7 of the drawings, the keys controlling the return under power of the carriage from any advanced position to a selected precedent position are mounted on the travelling carriage 14 and arranged in a novel manner to enable the selection of any of several precedent positions to which the carriage may be returned. The machine is provided with a key lever 122, the actuation of which causes the engagement of the carriage return clutch to effect the return movement of the carriage. The key lever 122 which extends along the left side wall of the carriage is pivoted at 124 to the rear portion of the carriage frame, and is acted upon by a coiled spring 123 which normally maintains the same in elevated position. This key lever extends forwardly to a point adjacent the keyboard of the key carriage and terminates in an upwardly projecting stem extending through a slot in a guide plate 126 secured to the inclined keyboard frame, the stem having a transverse stop pin 128 to limit the extent of depression of the key lever. A key 130 is fixed to the upper end of said stem and the depression of this key causes the return of the carriage to its limiting left hand position.

A bell crank lever 132 pivoted at 124 concentrically with the key lever 122, depends from this pivot pin, the depending arm constituting a support for an extension 134 adjustably secured, as by a pin and slot connection 136 and a pivot 138 spaced therefrom, to the depending arm of the bell crank. This extension is slotted as at 140 to embrace a stud 142 on a radial arm 144 secured to a horizontal rock shaft 146 journaled in bearings on the key carriage frame. This shaft extends part way toward the right hand side of the key carriage and at its inner end carries an arm 148 depending through a slot in the apron 32 to a point in proximity to and behind the trip bail 64.

The remaining shorter arm of the bell crank 132 projects forwardly substantially parallel with and below the key lever 122 and the free end of said arm is provided with a lip 150 formed thereon to contact normally a rigid headed pin 152 projecting from the left side of the key carriage

14 which arrests the parts at one extreme of their movement.

A restoring spring 154 (Fig. 1), encircling the shaft 146, yieldingly retains the arm 148 withdrawn from the trip bail 64, the headed pin 152 serving to limit the clockwise rotation of these parts under the influence of the spring 154 and to confine the parts against lateral displacement.

A by-pass pawl 156 pivoted at 158 intermediate between the ends of and depending from the key lever 122, is turned clockwise by a spring 160 until its free reduced end is arrested by contact with the fixed pin 152, in such position as to lie in line with the lip 150 on the short arm of the bell crank 132. The key lever 122, when depressed, forces the reduced end of the by-pass pawl 156 against the lip 150 of the short arm of the bell crank 132, and rocks the bell crank clockwise (Figs. 1, 2 and 7). This movement of the bell crank, through arm 144 and shaft 146 rocks the arm 148 counter-clockwise against the trip bail 64 to actuate said bail to close the carriage return clutch 40, 42 so that the carriage is returned toward the beginning of a line.

The depression of the key lever 122 to its fullest extent brings the sharply inclined edge 162 of the by-pass pawl into wiping contact with the limit pin 152 which operates to cam the by-pass pawl off from the lip 150. When this occurs the spring 154 restores the arm 148, shaft 146, arm 144, and bell crank 132 to their normal positions irrespective of and uncontrolled by the key lever 122. This enables the key lever 122 to be operated by respectively different strokes to effect the complete and the partial return movement of the carriage as will hereinafter appear.

To enable the carriage to be arrested in different return positions, each short of a complete return to the left hand marginal position, the machine is provided with a second key lever 164 having a stem projecting upwardly through the guide plate 126 above the stem of the key lever 122 and having a key 166 fixed to the upper end of said stem and with a third key lever 168 having a stem projecting upwardly through said guide plate above and to the rear of the stem of the lever 164 and having a key 170 fixed to the upper end of said stem. The key lever 168 extends downwardly and rearwardly across the left hand end of the key carriage 14 and its lower end engages behind a guide plate 172 secured at its rear edge to the outer face of an abutment 174 depending a predetermined distance below the left hand lower corner of the key carriage 14.

The inner face of the guide plate 172 is vertically grooved, to accommodate slidingly a check stop 176 secured to the lower end of the key lever 168. The lever 168 is acted upon by a coiled return spring 178 which normally holds the lever yieldingly in its uppermost position.

The lever 164 is pivoted at 180 on the lever 168 and, upon being depressed, is arranged to actuate the lever 168 through an eccentric 182 fixed to, and rotatably adjustable on, the lever 164 and engaging in a slot 183 in the lever 168. This slot provides lost motion between the lever 164 and the lever 168, the amount of which may be regulated by adjusting the eccentric 182.

In order that the lever 122 may be depressed to throw the carriage return mechanism into operation by the depression of either the key lever 164 or the key lever 168, the lever 122 carries a pin 184 secured in an upwardly projecting portion of the lever and engaged by the lever 164 during the downward movement of the latter le-

ver. This pin engages in a slot 196 in the lever 164 and forms a guide for said lever but permits the lever 122 to be depressed freely independently of the lever 164.

The pin 128 constitutes a stop limiting the 5 downward movement of the levers 164 and 168 as well as the lever 122. The upward movement of the lever 164 is limited by the engagement of a stop face 188 formed on said lever with the under side of the guide plate 126. This limits 10 also the upward movements of the lever 122 and of the lever 168.

The mechanism cooperating with the check stop 176 to arrest the return movement of the carriage has the same construction, arrangement and mode of operation as the corresponding mechanism illustrated and described in applicant's application Serial No. 149,571. Said mechanism comprises a draft rod 190 extending transversely of the line space frame. This rod is T-shaped in cross section and is arranged to slide 15 in a channel formed by the rear rail 11 of the line space frame, the web 192 projecting forwardly therefrom and the carriage escapement rack 192 which is secured to the forward edge of said 20 web.

The left hand end portion of the draft rod 190 is toothed for a considerable distance and arresters 194, 196 and 198 of different heights are 25 adjustably arranged on the draft rod to be engaged respectively by the fixed abutment 174 and the check stop 176 to arrest the carriage during its return movement at any one of three precedent positions and also to effect a line spacing operation incident to its return to any of such precedent position. The arrester 194 of least height is located farthest to the right and the arresters 196 and 198 of successively greater heights are mounted on the draft rod in corresponding order to the left of the arrester 194. These arresters preferably have substantially the same construction as illustrated and described in applicant's application Serial No. 149,571, to enable them to be readily adjusted longitudinally on the draft rod.

The left hand end of the draft rod 190 passes through an aperture in a rearwardly turned slotted projection 200 on the left hand end of a slide 202 extending therefrom toward the right along the front face of the carriage escapement rack 192 to which the slide is connected by headed fastenings 204 engaging in slots 206 in the slide. The slide operates to guide the draft rod in its endwise travel and prevents it from canting in its channel.

The draft rod is provided at its right hand end with a threaded portion 208 passing through a block 210 secured to the forward face of an arresting plate 212, the draft rod being secured to said block by means of nuts 214 threaded on the rod and located upon opposite sides of the block. The arresting plate 212 is provided with parallel slots 216 and 218 through which pass respectively a headed fastening 220 and a stub shaft 222 to support and guide the plate.

The arresting plate 212 is formed with a beak 224 which projects toward the left from the upper left hand edge of the plate into position to collide with a forwardly extending fixed stop 226 (Fig. 1) rigidly secured to the right hand end of the rear rail 11.

A coiled spring 228 secured at one end to the fixed stop and connected at its opposite end to the draft rod 190 yieldingly retains the arresting plate 212, the draft rod and the slide 202 at their

right hand limits of travel as determined by contact of the left end wall of the slot 216 in the arresting plate with its guiding and supporting stud or headed fastening 220.

When the operator, at any point in the advance of the carriage, desires to return the carriage to its limiting left hand position or to give a full return movement to the carriage, he depresses the key 130 and key lever 122 to their limiting positions determined by the engagement of the stop pin 128 with the guide plate 126. During the downward movement of the lever, the bell crank 132 is actuated to engage the carriage return clutch after which the pawl 156 is cammed off the lip 150 of the bell crank lever so that the key lever exercises no further control on the bell crank and the parts operated thereby. After actuation by the key lever, the parts of the clutch engaging mechanism between the arm 148 and the clutch are maintained in position until the carriage approaches the end of its return movement. The check stop 176 is not depressed by this operation but remains in its uppermost position.

During the return movement of the carriage, the fixed abutment 174 passes over the graduated arresters 194 and 196 and finally engages the highest arrester 198, the location of which on the draft rod determines the beginning of a line of 30 writing.

The abutment 174, upon contact with the abrupt right hand face of the arrester 198, forces the arrester to the left and with it the draft rod 190 and arresting plate 212, tensioning the return 35 spring 228, until the beak 224 impinges against the fixed stop 226 which positively arrests further travel of the draft rod and the arrester 198 leftwardly and hence arrests the carriage 14 in its predetermined extreme leftward position to define the left hand margin and the beginning of the writing line.

A slight play is arranged between the right hand end of the draft rod and the block 210 to enable the escapement to lock the carriage at a 45 uniform point upon each return of the carriage.

As the draft rod is moved to the left by the final movement of the carriage, the carriage return clutch is disengaged by mechanism hereinafter described.

When the operator desires to arrest the return movement of the carriage in a position to the right of the full return position as determined by the arrester 196, he depresses the key 166 and the key lever 164. The depression of the key 50 lever 164 depresses the lever 122 through the engagement of the lever 164 with the pin 184 to throw the carriage return mechanism into operation, the movement of the lever 122 and the lever 164 being limited by the engagement of the pin 128 with the guide plate 126. During 55 the downward movement of the lever 164, the eccentric 182 engages the lower side of the slot in the lever 168 and said lever is moved downwardly to project the stop 176 downwardly to a 60 position such that it will clear the arrester 196 but will engage the arrester 196 during the return movement of the carriage. During the return movement of the carriage, the check stop 176 passes over the arrester 194 and engages the 65 arrester 196 as the carriage approaches the end of its return movement and slides the draft rod to the left in the same manner as before until the movement of the carriage is finally stopped by the engagement of the beak 224 on the slide 70 212 with the fixed stop 226.

When the operator desires to arrest the return movement of the carriage in a position to the right of the partial return position determined by the engagement of the check stop with the arrester 196, he depresses the key 170, and key lever 168. The depression of this key lever 168 depresses the lever 164 through the engagement of the eccentric 182 with the upper side of the slot 183 in the lever 168 and the depression of the lever 164 depresses the lever 122 through the engagement of said lever 164 with pin 184, the movement of the levers being limited by the engagement of the pin 128 with the guide plate 126. The depression of the lever 122 throws into operation the carriage return mechanism as before. The downward movement of the lever 168 projects the stop 176 to a lower position than that into which it is projected by the depression of the lever 164 to cause the stop to engage the arrester 194 during the return movement of the carriage. As the carriage executes its return movement under the action of the power mechanism, the check stop 176 engages the arrester 194 thereby moving said arrester and the draft rod 190 to the left until the movement of the carriage is stopped by the engagement of the beak 224 with the stop 226.

It is highly desirable that the mechanism for stopping the return movement of the carriage in the two partial return positions should be maintained operative after a quick depression and release of either of the keys 166 and 170. Otherwise, it would be necessary for the operator to maintain each of these keys in depressed position during the return of the carriage in order to stop the carriage in the desired partial return position. In order to secure this result, mechanism is provided for holding the check stop 176 in either of the positions into which it is projected by these keys respectively after the quick depression and release of the key.

The mechanism for holding the check stop in position comprises a latch bar 230 pivoted upon a stud 232 secured in a projection on the lever 168 and depending therefrom in the manner clearly shown in Figs. 5, 6 and 7. The latch bar is loosely pivoted on the stud 232 so that not only can the stud turn freely within the latch bar, but the latch bar can swing freely in a vertical plane containing the axis of the stud. The latch bar extends downwardly from the lever 168 through an opening 234 in a guide plate 236 formed on a bracket 238 secured to the side of the deck 34 of the key carriage. The latch bar is formed with notches 240 and 242 arranged to receive alternatively a catch 244 formed by the beveled edge of the guide plate 236 to hold the latch in either of two depressed positions. The latch bar is acted upon by a leaf spring 246 secured to the stud 232 and bearing against the outer face of the latch bar which normally maintains the latch bar in engagement with the edge of the catch 244.

When the key 166 and key lever 164 are depressed to their limiting positions, the latch bar is depressed to a point at which the catch 244 engages in the lower notch 240 to hold the lever 168 in position to locate the check stop 176 to engage the arrester 196 during the return movement of the carriage. When the key 170 and lever 168 are depressed to their limiting positions, the latch bar is depressed into position to cause the catch 244 to engage in the upper notch 242 to hold the lever 168 in position to locate the

check stop 176 to engage the arrester 194 during the return movement of the carriage.

The latch bar is arranged to hold the lever 168 and the stop 176 carried by said lever in the position into which they are moved by the depression of a key during the return of the carriage. Thereafter the latch bar is actuated to release the catch 244 from the notch in the latch bar in which it is engaged by any one of a number of normal machine operations and the lever 168 is then moved upwardly to its upper limiting position by the return spring 178.

The latch bar is swung outwardly to disengage the catch 244 from the notch in the latch bar by the depression of a type key lever.

In the present construction a ribbon vibrator mechanism is employed having substantially the same construction, arrangement and mode of operation as the corresponding mechanism illustrated and described in the patent to Foothorap No. 1,286,573, dated December 3, 1918. This mechanism comprises a vibrator lever 248 pivoted on a stud 250 secured in a bracket 252 attached to the deck 34 of the machine head. This vibrator lever is formed with an upwardly extending arm having an arcuate slot 256 in which engages a pin 258 fixed in the forward end of a link 260, the rear end of which is pivoted at 262 to the downwardly extending arm 264 attached to the universal bar rocker 266. The pin 258 also engages in a slot 268 in a vertically adjustable shifter 270 mounted to slide vertically upon a bracket 272 attached to the framework of the machine head. The universal bar rocker is provided with forwardly extending arms 274 from which are suspended the hangers 276 which carry the universal bar 278. This bar underlies an abutment screw 280 mounted on each of the type key levers one of which is shown in Fig. 4 and is indicated at 282. Each of these levers is pivoted on the transverse shaft 284 and is provided, at its forward end, with a key 286 by which the lever is depressed and with a return spring 287 by which the lever is restored to normal position.

The arm 264 is acted upon by a return spring 289 and the lever 248 is acted upon by a return spring 291 which springs tend to restore the rocker 266 and the lever 248 to normal positions after each depression of the universal bar. Upon the depression of the type key lever, the universal bar is depressed therewith and through the connections described, the ribbon vibrator lever 248 is swung in a counter-clockwise direction, Figs. 2 and 4, this movement advancing the lower arm of the lever.

The lower arm of the ribbon vibrator lever carries a cam plate 288 fixed thereto and having an inclined cam face 290 (see Fig. 1) for engaging the inner side of the latch bar 230. When the carriage return key levers 164 and 168 are in their uppermost positions, the lower end of the latch bar 230 lies above the cam plate 288 so that the cam plate does not engage the same during the movements of the vibrator lever. When either of said carriage return key levers is depressed, the latch bar 230 is moved downwardly to carry the lower end thereof below the cam plate 288 which then occupies a position to the rear of the latch bar and the latch bar is retained in this position by the engagement of the catch 244 in one of the notches 240, 242. Then upon the depression of a type key lever, the forward movement of the lower arm of the lever 248 carries the cam plate 288 into engagement with the latch bar and the latch bar is swung to the left (Figs.

5 and 6) to release the same from the catch. The key lever 168 and the stop 176 are then restored to their uppermost positions by the action of the spring 178.

Upon the release of the type key lever, the universal bar is lifted to its normal position and the ribbon vibrator lever 248 is swung back in a clockwise direction to its initial position by the action of the return springs 289 and 291.

The machine is provided with a decimal tabulator mechanism having substantially the same construction arrangement and mode of operation of parts as the corresponding mechanism illustrated and described in the patent to Foothorap No. 1,280,697, dated October 8, 1918. The present machine is provided with mechanism which, upon the depression of any one of the decimal tabulator keys in the next operation following the return of the carriage to a partial return position, will swing the latch bar 230 outwardly to disengage the same from the catch 244 and thereby release the lever 168 and the check stop 176.

The decimal tabulator stop mechanism comprises the usual series of decimal tabulator key levers one of which is shown in Fig. 2 and is indicated at 296. Each of these levers is pivoted at its rear end to a bearing member depending from the cover plate 298 and is yieldingly held in its uppermost position by a retracting or return spring 300. Each of the decimal tabulator key levers is arranged to engage the upper side of the bail 302 pivoted at 304 upon bearings suspended from the cover plate and extending transversely beneath the several levers, the bail being normally held in elevated position by a spring 305. To the bail is secured a forwardly extending arm 306 carrying at its forward end a pin 308 engaging in a slot 310 in a cam lever 312 pivoted at 314 upon the side plate of the machine head. To the lower end of the lever 312 is attached a cam plate 316 arranged to extend behind the latch bar 230 as clearly shown in Fig. 3.

When the parts are in their normal positions, the angular location of the lever 312 is such that the cam 316 occupies its rearward position so that it does not engage the latch bar 230. With the above construction, upon the depression of any one of the decimal tabulator keys the bail 302 is swung downwardly and through the connection between said bail and the lever 312, said lever is swung in a counter-clockwise direction (Fig. 2). If the lever 168 and the check stop 176 are then held in depressed position by the engagement of the catch 244 with one of the notches 240, 242 in the latch bar, the movement of the lever 312 will engage the cam 316 with the inner side of the latch bar 230 and said bar will then be swung outwardly to disengage the same from the catch and thereby release the lever 168 and said check stop.

The present machine is also provided with a column tabulator mechanism having substantially the same construction, arrangement and mode of operation of the parts as the corresponding mechanism illustrated and described in said Foothorap Patent No. 1,280,697. This mechanism comprises a column tabulator key lever 318 pivoted at 320 on the frame of the machine. This lever is arranged to throw out the holding dog of the usual escapement mechanism and to interpose a stop on the carriage in the path of a fixed stop mounted on the tabulator bar to stop the carriage in a predetermined columnar position. The mechanism for throwing out the escapement dog and for actuating the stop mechanism to

interpose the stop on the carriage in the path of the fixed stop on the tabulator bar preferably has substantially the same construction and mode of operation as the corresponding mechanism illustrated and described in said patent and is, therefore, not disclosed herein.

The mechanism for releasing the latch bar 230 from the catch 244 upon the depression of the column tabulator key lever comprises a rocker bail indicated generally at 322 and having a body 324 which is inserted in a U-shaped portion 326 of the casing of the machine head in front of the keyboard and is held therein by screws 328. The right hand end (Fig. 3) of the rocker bail, is provided with a rearwardly extending arm 330 having a lateral extension 332 which projects beneath the column tabulator key lever 318 as shown in said figure. The bail 322 is provided at its left hand end (Fig. 3) with a rearwardly extending arm 334 having a lateral extension 336 located above the forwardly extending arm of a latch throwout lever 338 pivoted at 340 on the side plate of the carriage. The downwardly and rearwardly extending arm of this lever is formed with a cam 342 arranged to engage the inner side of the latch bar 230. The latch throwout lever 338 is acted upon by a coiled spring 344 which tends to swing the same in a counter-clockwise direction (Figs. 2 and 7) and to carry the cam 342 out of position to engage the latch bar 230.

The throwout lever 338 is connected by a coiled spring 345 with a projection on the lever 168, this spring acting in opposition to the spring 344. When the lever 168 is in elevated position, the spring 345 is distended so that its tension is sufficient to overcome the tension of the spring 344 and the lever 338 will therefore be maintained in the position shown in Fig. 2, the movement of the lever under the tension of the spring 345 being limited by the engagement of a projection 347 on the lever with the bracket 238. When the lever 168 is depressed, the tension exerted by the spring 345 is diminished so that it will be overcome by that of the spring 344 and the lever 338 will be maintained substantially in the position shown in Fig. 7.

With the parts in their normal positions as shown in Fig. 2, in which the lever 168 is in elevated position, the lever 338 is held by the spring 345 in the position shown in this figure with the cam 342 in engagement with the latch bar 230. It will be noted that with the lever 338 in this position, the forwardly extending arm of said lever lies slightly below the extension 336 on the bail 322 and said bail is held by gravity in depressed position with said extension resting on a contact surface on the frame. Upon the depression of the carriage return key lever 168, the lever 338 is swung by the spring 344 in a counter-clockwise direction into the position shown in Fig. 7, thereby disengaging the cam 342 from the latch bar 230 to allow said bar to swing inwardly to engage the catch 244 in one of the notches 240, 242 and the forwardly extending arm of the lever 338 engages the extension 336 on the bail thereby swinging the bail upwardly into operating position as shown in said figure.

Because of the fact that when the lever 168 is in its normal elevated position, the bail 322 is allowed to assume its depressed position by the position of the lever 338, the bail is not then engaged by the column tabulator lever 318 or any of the levers by which it is actuated to release the latch bar 230.

With the parts in the positions shown in Figs.

5 and 7 in which the lever 168 is in depressed position and the catch is engaged in one of the notches of the latch bar to hold the lever 168 and stop 176 in depressed position, upon the depression of the column tabulator key, the bail 322 is actuated by the engagement of the column tabulator key lever with the extension 332 to swing the extension 336 downwardly, the bail being swung from the position shown in Fig. 7 to the position shown in Fig. 2. During this movement of the bail, by the engagement of the extension 336 with the forwardly extending arm of the lever 338, said lever is swung in a clockwise direction thereby moving the cam 342 rearwardly. The engagement of the cam 342 with the latch bar swings said bar outwardly to disengage the same from the catch thereby releasing said lever 168 and stop 176 and allowing them to be moved upwardly to their normal positions.

The present machine is provided with a release key lever 346 and with mechanism operated by the depression of said lever for holding out the holding dog of the escapement mechanism to allow free movement of the type carriage while the lever is depressed. The connections between the release key lever and the escapement mechanism for releasing the holding dog have substantially the same construction, arrangement and mode of operation as the corresponding mechanism illustrated and described in the patent to Foothorap No. 1,203,519, and are therefore not disclosed herein.

The release key lever is pivoted on the shaft 264 and its forward end extends over the lateral extension 332 on the bail 322 as shown in Fig. 3, the release key lever being located some distance above the column tabulating key lever as shown in Fig. 4. A link 348 is pivotally suspended at 350 upon the release key lever and is formed at its lower end with a slot 352 in which engages the lateral extension 332 on the bail 322.

With the lever 168 and stop 176 held in depressed position by the engagement of the catch 244 in one of the notches of the latch bar, upon the depression of the release key lever, the link 348 engages the lateral extension 332 on the bail when said extension reaches the upper end of the slot 352 and the bail is thereby swung in a direction to depress extension 336 at the opposite end thereof. This movement of the bail 50 swings the latch bar throwout lever 338 in a clockwise direction from the position shown in Fig. 7 in substantially the same manner as by the depression of the column tabulator key lever above described, and the latch bar will be actuated to release the same from the catch and allow the lever 168 and the stop 176 to be moved back upwardly to normal position.

The present machine is provided with a space bar 354 fixed to forwardly extending arms on a space bar yoke 356 pivoted on the shaft 353 extending across the machine and connections are provided between the space bar yoke and the escapement mechanism for controlling the escapement. These connections preferably have substantially the same construction, arrangement and mode of operation as the corresponding mechanism illustrated and described in said patent to Foothorap No. 1,203,519 and are not disclosed herein.

Mechanism is provided for releasing the latch bar 230 from the catch 244 upon the depression of the space bar. This mechanism comprises an arm 360 secured to the body 324 of the bail 322 and extending beneath the forward end of one 75

of the arms on the yoke 356 adjacent the space bar as shown in Fig. 3 and arranged to be engaged by said arm.

With the lever 168 and stop 176 held in depressed position by the engagement of the catch 244 in one of the notches in the latch bar, upon the depression of the space bar, the arm 360 on the bail 322 is engaged by the adjacent arm of the yoke 356 and the bail is swung in a direction to depress the lateral extension 336. This movement of the bail actuates the latch bar throwout lever 338 in substantially the same manner as by the depression of the column tabulator key described above, to release the latch bar from engagement with the latch and allow said lever 168 and stop 176 to move upwardly to their normal positions.

The machine is provided with the usual line space brake release lever indicated at 361 pivoted on the shaft 353. The forward end of this lever is provided with a laterally bent portion 363 which extends over the forwardly extending arm of the lever 338. With the lever 168 and the check stop 176 held in depressed position by the engagement of the catch 244 in one of the notches in the latch bar, upon the depression of the forward end of the lever 361, the lever 338 will be engaged by the lever 361 and swung in a counter-clockwise direction (Fig. 7) to release the latch bar from said catch and allow the lever 168 and said stop to move upwardly to their normal positions.

The disconnection of the motor from the carriage is automatically effected regardless of the extent of return travel of the carriage by a mechanism adapted to function just prior to the arrest of the carriage at any of its completely or partially returned stations. The said mechanism comprises a floating thrust bar 365 slidably supported adjacent its left hand end in an eye 367 formed in a bracket secured to and projecting from the adjacent vertical bracket 8 on the line space frame. The thrust bar is slotted at its right hand end as at 369 to ride on the rear end of a stud 371 projecting rearwardly from and travelling with the arresting plate 212. The left hand end of the thrust bar is arranged to engage an inclined cam face on a member 373 secured to the right hand end of the trip bail 64 in the path of travel of the thrust bar.

The length of the slot 369 in the thrust bar is less than the distance normally between the beak 224 and the fixed stop 226. Therefore, as the arresting plate 212 is drawn to the left by contact of the abutment 174 with the arrester 198 or by contact of the check stop 176 with either of the arresters 194 or 196, the supporting stud 371 will travel idly along the slot 369 of the thrust bar until just prior to the arrest of the plate 212 by contact of the beak 224 with the stop 226, the supporting stud 371 reaches the left end wall of the slot 369. Thereafter, the continued movement of the arresting plate 212 shifts the thrust rod to the left against the inclined face of the contact member 373 on the trip bail and rocks the trip bail back to its normal position, thereby disconnecting the shiftable driven clutch member of the carriage return clutch from the driving clutch member.

In the construction shown in Figs. 8, 9 and 10, the machine is provided with three carriage return keys for throwing the carriage return drive mechanism into operation and for projecting the partial carriage return stop into selected

operative position when the carriage is to be stopped in either of two partial carriage return positions. The key lever 122a which is pivoted at 124a and carries the key 130a, the key lever 164a which is pivoted at 180a on the key lever 168a and carries the key 166a, and the key lever 168a which carries the key 170a, except as hereinafter described, all have substantially the same construction, arrangement and mode of operation as the corresponding mechanism shown in Figs. 1 to 7 inclusive.

The lever 122a operates the lever 132a to throw in the carriage return mechanism by the engagement of the pawl 156a pivoted at 158a on the lever 122a with the arm 150a of the lever 132a. The connections between the lever 132a and the carriage return clutch have substantially the same construction, arrangement and mode of operation as the connections between the lever 132 and the clutch shown in Figs. 1 to 7, inclusive.

The key lever 122a carries a pin 128a which engages the cover plate 126a to limit the downward movement of the lever 122a. The lever 122a is provided with a slightly yielding projection 364 on the key which is engaged by a projection 364 on the key lever 164a so that the lever 122a is depressed by the depression of the lever 164a. The lever 164a carries an eccentrically mounted stud 182a engaging in a slot 183a in the lever 168a to provide a lost motion connection between the two levers, the lever 168a being depressed with the lever 164a through the engagement of the stud 182a with the lower side of the slot. The lever 168a is guided in its vertical movements by the engagement of the stop 176a behind the guide plate 172a and by a headed stud 366 secured to the cover plate 126a and engaging in a slot 368 in the upper portion of the lever 168a.

The mechanism for holding the lever 168a and the check stop 176a in either of the positions into which they are projected by the depression of either of the keys 170a and 166a, in the construction shown in Figs. 8, 9, and 10, comprises a longitudinally movable latch bar 370 pivotally supported at its lower end at 372 upon the vertical extending arm of a bell crank lever 374 pivoted at 376 on the side plate of the type carriage. The latch bar 370 is slidably supported adjacent its upper end by means of a stud 378 secured in the side plate and engaging in the slot 380 in the latch bar. The latch bar carries a latch plate 382 having a beveled edge arranged to engage alternatively in the notches 384 and 386 formed in the upper part of the key lever 168. The latch bar is acted upon by a coiled spring 388 which tends yieldingly to move the same forwardly or to the right, (Fig. 8) thereby maintaining the latch plate 382 in engagement with the left hand opposed edge of the key lever 168a.

Fig. 8 shows the parts in their normal positions with the latch plate 382 held in engagement with the adjacent portion of the lever 168a by the action of the coiled spring 388.

Upon the depression of the lever 168a by the depression of key 170a, the lever 164a and the lever 122a are carried downwardly therewith and the movement of said levers is limited by the engagement of the stop pin 128a with the cover plate 126a. At the end of this movement of the lever 168a, the latch plate 382 is engaged in the notch 386 in said lever to hold the lever and the check stop 176a in position. This depression of the lever 168a depresses the stop 176a

5 into position to engage the arrester 194 to arrest the carriage in one partial return position. Upon the depression of the key lever 164a by the depression of key 166a, the levers 168a and 122a are carried downwardly therewith and the movement of said levers is again limited by the engagement of the stop pin 128a with the cover plate 126a. The downward movement of the lever 168a produced by the depression of the lever 164a carries the lever 168a downwardly into position to engage the latch plate 382 in the notch 384 in said lever. This depression of the lever 164a will depress the check stop 176a into position to engage the arrester 196 to arrest the carriage in another partial return position. The engagement of the latch plate 382 in either of the notches 384, 386 on the lever 168a will hold said lever and the check stop in position during the return of the carriage.

20 In order to disengage the latch plate 382 from either of the notches 384 and 386 and thereby release the lever 168a, the latch bar 370 is moved rearwardly or to the left (Fig. 8) against the tension of spring 388. As shown clearly in this figure, the horizontally extending arm of the bell crank 374 is arranged to be engaged by the lateral extension 336a on the bail 322a.

25 This bail has the same construction and arrangement as the bail 322 shown in Figs. 1 to 7 inclusive, and is operated in the same manner by the release key lever, the column tabulator key lever and the space bar. When the lever 168a is in elevated position and the latch bar 370 is held in its rearward position by the engagement of the latch plate 382 with the opposed face of the lever 168a, the bell crank lever 374 is located in the position shown in Fig. 8 with its horizontally extending arm lowered. The bail 322a is then located in lowered position as shown in said figure so that it is not actuated by the release key lever, the tabulator key lever or the space bar. Upon the depression of the lever 168a and the shifting of the latch bar 370 forwardly to engage the latch plate 382 in one of the notches 384, 386, the bell crank lever 374 is swung into the position shown in Fig. 10. By this movement of the bell crank lever, the bail 322a is swung upwardly into operating position as shown in said figure. With the bail in this position, upon the depression of the bail produced by the depression of the release key, the column tabulator key or the space bar, the bell crank lever 374 is swung in a clockwise direction (Figs. 8 and 10) by the engagement of the extension 336a on the bail therewith and the latch bar 370 is moved rearwardly to release the lever 168a and allow the same and check stop 176a to move upwardly to their normal positions.

30 The latch bar 370 is also actuated to disengage the latch plate from either of the notches in the lever 168a and thereby release said lever by the depression of any one of the decimal tabulator keys. In the construction shown in Figs. 35 8, 9 and 10, the universal bar 278a is suspended upon hangers 276a pivotally supported upon arms 274a fixed to the rocker 256a, this rocker being acted upon by the usual return spring. Upon one of the arms 274a is formed a projection 390 having a cam face 392 arranged to engage a roll 394 mounted upon the rear end of the latch plate 370.

35 40 45 50 55 60 65 70 75 80 85 90 95 100 As the universal bar 278a is swung downwardly by the depression of a type key, the arm 274a is swung downwardly therewith about the axis

of the rocker 266a. When the parts are in their normal positions with the key lever 168a elevated, the latch bar 370 is held back by the engagement of the latch plate 382 with the lever so that the cam 392 does not then engage the roll 394. When the lever 168a is depressed and the latch bar 370 has advanced to engage the latch plate 382 in one of the notches 384, 386 in the lever, the roll 394 is then carried forwardly into position to be engaged by the cam 392. With the parts in this position, upon the depression of a type key and the downward movement of the universal bar produced thereby, the cam 392 will be swung downwardly into engagement with the roll 394 and the latch bar 370 will be moved rearwardly to release the key lever 168a.

The latch bar is also actuated to release the key lever 168a, by the depression of a decimal tabulator key. Fig. 8 shows a decimal tabulator key lever 296a and a bail 302a pivoted at 304a which, upon the depression of a tabulator key lever, is engaged by said lever and swung downwardly. Upon one of the side arms of the bail 302a is fixed a cam arm 396 having a cam face 398 arranged to engage the roll 394.

When the parts are in their normal positions, with the lever 168a elevated and the latch bar retracted, the roll 394 is located out of the path of the cam arm 396. When the key lever 168a is in depressed position and the latch bar 370 has advanced to engage the latch plate 382 in one of the notches 384, 386, in said lever, the roll 394 is carried into the path of the cam arm 396. Then upon the depression of the bail 302a produced by the depression of any one of the tabulator keys, the cam face 398 on cam arm 396 is engaged with the roll 394 and the latch bar 370 is moved rearwardly to release the lever 168a.

The construction shown in Figs. 8, 9 and 10 comprises a line space brake release lever 361a constructed and pivoted in substantially the same manner as the lever 361 shown in Figs. 1 to 7 inclusive. The lever 361a is provided with a lateral bend extending over the horizontal arm of the bell crank lever 374 and arranged to engage said arm upon the depression of the forward end of the lever 361a when the parts are in the positions shown in Fig. 10. By the engagement of the lever 361 with the bell crank lever 374 the latch bar will be actuated to release the lever 168a. When the lever 168a is in elevated position, the bell crank lever is located in the position shown in Fig. 8 in which the horizontal arm thereof is not engaged by the lever 361a upon the depression of the forward end of said lever.

It is to be understood that, except as defined in the claims, the invention is not limited to the particular construction and arrangement of parts of the illustrated embodiment of the invention but that the invention may be embodied in other forms within the scope of the claims.

Having explained the nature and object of the invention and having specifically described a construction embodying the invention in its preferred form, what is claimed is:

1. In a record making machine, a carriage movable in opposite directions across the machine, means for moving the carriage in one direction to letter space, power mechanism for imparting return movements to the carriage, controlling means for causing the power mechanism to return the carriage and for causing the stoppage of the carriage substantially at a predetermined position, said controlling means being normally held in inactive position, means for moving

said controlling means into active position, mechanism for holding certain parts of said controlling means in position to cause the stoppage of the carriage during the return of the carriage, 5 a type key lever and means operated upon the manipulation of the type key lever for releasing said holding mechanism.

2. In a record making machine, a carriage movable across the machine in opposite directions, means for moving the carriage in letter spacing direction, power operated mechanism for returning the carriage, means for discontinuing the return movement of the carriage comprising a device normally located out of operative position, means for locating said device in position to discontinue the carriage movement, mechanism for retaining said device in the latter position during return movement of the carriage, a type bar actuating mechanism, a universal bar 10 operated by said mechanism and means actuated by the universal bar for releasing said retaining mechanism.

3. In a machine of the class described, a carriage movable in opposite directions across the machine, means for moving the carriage in one direction to letter space, power mechanism for imparting return movements to the carriage, devices for causing the stoppage of the return movement of the carriage, normally located relatively out of operative positions, means for locating relatively said devices in positions to cause the stoppage of the carriage, mechanism for holding said devices relatively in operative positions after being located by said means, a type bar actuating mechanism, a ribbon vibrator operated by the type bar actuating mechanism and means actuated by the ribbon vibrator for releasing said holding mechanism.

4. In a record making machine, a carriage movable in advance and return directions transversely of the machine, mechanism for moving the carriage in an advance direction during a record making operation, escapement mechanism for controlling said advance movement, power operated mechanism for returning the carriage, means for causing the stoppage of the return movement of the carriage, mechanism for locating certain parts of said means out of operative position, mechanism for positioning said parts to cause the 40 stoppage of the return movement of the carriage, mechanism for holding said parts in said position, a manipulative device for releasing the carriage from the escapement mechanism for advance movement and mechanism operated upon the 45 actuation of said device for throwing out said holding mechanism.

5. In a record making machine, a transversely movable carriage, means for moving the carriage across the machine in one direction, an escapement mechanism for controlling the advance of the carriage, power means, mechanism operated by the power means for returning the carriage in the opposite direction, controlling devices to cause the power means to return the carriage and to cause the stoppage of the carriage substantially at a predetermined position, mechanism for holding certain elements of said devices out of operative position, mechanism for locating said elements in position to cause the stoppage of the carriage, means for retaining said elements in operative position after being located by said mechanism, a manually controlled device for releasing the carriage from the escapement mechanism, a transversely extending bail operated by said device and mecha-

nism operated by said bail for releasing said retaining means.

6. In a machine of the class described, a carriage movable transversely across the machine, means for moving the carriage in one direction, an escapement mechanism for controlling the advance of the carriage, power mechanism for returning the carriage in the opposite direction, devices for causing the arrest of the return movement of the carriage, means for holding certain parts of said devices in inoperative position, means for positioning said parts to cause the arrest of the carriage, a latch for holding said parts in the latter position, a manipulative release device for releasing the carriage from the escapement mechanism, a bail extending transversely of the machine and operated upon the actuation of said release device and a lever operated by the bail for throwing out said latch.

7. In a machine of the class described, a transversely movable carriage, mechanism for moving the carriage in one direction during a record making operation, power means for returning the carriage, means for discontinuing the return movement of the carriage, certain parts of which are normally held out of operative position, mechanism for moving the latter parts into position to discontinue the carriage movement, mechanism for holding the latter parts in operative position, a manipulative column tabulator control device and mechanism for releasing said holding mechanism upon the actuation of said device to tabulate the carriage.

8. In a record making machine, a carriage mounted for movement across the machine, mechanism for advancing the carriage during a record making operation, means operated by power for imparting return movements to the carriage, devices for causing the discontinuance of the return movement of the carriage, means for locating one of said devices in inoperative position, mechanism for shifting the latter device into position to cause the arrest of the carriage, means for holding the latter device in position upon being located by said mechanism, a manually operable column tabulator control member, a transversely extending bail operated upon the actuation of said control member to tabulate the carriage and mechanism actuated by said bail for releasing said holding means.

9. In a machine of the class described, a carriage, means for moving the carriage in one direction across the machine during a record making operation, power mechanism for imparting return movements to the carriage, controlling devices for causing said mechanism to return the carriage and for causing the stoppage of the carriage substantially at a predetermined position, means for normally holding said devices relatively in inoperative positions, means for relatively positioning certain parts of said devices to cause the stoppage of the return movement of the carriage, a latch for holding said parts relatively in operative positions during the return movement of the carriage, a manipulative column tabulator lever, a bail extending transversely of the machine and operated under control of said tabulator lever and a lever actuated by said bail for releasing the latch upon the actuation of the tabulator lever to tabulate the carriage.

10. In a machine of the class described, a carriage movable in opposite directions across the machine, means for moving the carriage in an advance direction, power mechanism for returning the carriage, a device for causing the arrest

of the return movement of the carriage, means for locating said device normally out of operative position, means for positioning said device to cause the arrest of the carriage, mechanism for holding said device in the latter position, a manipulative decimal tabulator control member and means for releasing said holding mechanism upon the actuation of said member to tabulate the carriage.

10 11. In a record making machine, a transversely movable carriage, mechanism for moving the carriage in one direction during a record making operation, power mechanism for returning the carriage in the opposite direction, means normally located out of operative position to cause the stoppage of the return movement of the carriage with the carriage in a predetermined position, mechanism for locating said means to cause the stoppage of the carriage movement, mechanism for holding said means in the latter position during the return of the carriage, a manually controlled device for causing the decimal tabulation of the carriage, a transverse bail operated by said device and mechanism actuated by said bail for releasing said holding mechanism upon the actuation of said device to tabulate the carriage.

15 12. In a machine of the class described, a carriage, means for moving the carriage in one direction across the machine during a record making operation, power mechanism for imparting return movements to the carriage, controlling devices for causing said mechanism to return the carriage and for causing the arrest of the carriage substantially at a predetermined position, means for holding said devices relatively out of arresting positions, mechanism for relatively positioning certain parts of said devices to cause the arrest of the carriage, a latch for holding said parts relatively in carriage arresting positions during the return of the carriage, a member under manual control for causing the decimal tabulation of the carriage, a bail extending transversely of the machine and operated by said member and a lever actuated by said bail to release the latch upon the actuation of said member to tabulate the carriage.

13. In a machine of the class described, a transversely movable carriage, mechanism for moving the carriage in an advance direction, power mechanism for returning the carriage in the opposite direction, means for causing the arrest of the return movement of the carriage, mechanism for holding certain parts of said means in inoperative position, means for locating said parts in position to cause the arrest of the carriage, retaining means for holding said parts in the latter position, a manually controlled spacing device and mechanism operated by said spacing device for releasing said retaining means upon the actuation of said device to space the carriage.

14. In a machine of the class described, a carriage movable in opposite directions across the machine, mechanism for moving the carriage in one direction during a record making operation, power mechanism for imparting return movements to the carriage, means for discontinuing the return movement of the carriage, certain parts of which are normally located out of operative position, mechanism for positioning said parts to discontinue the movement of the carriage, mechanism for holding said parts in the latter position during return movement of the carriage, a device under control of the operator

for spacing the carriage and a transversely extending bail operated by said device for releasing said holding mechanism upon the actuation of said device to space the carriage.

15. In a record making machine, a carriage movable across the machine in opposite directions, means for moving the carriage in advance direction, power operated mechanism for imparting return movements to the carriage, devices for causing the stoppage of the return movement of the carriage with the carriage in a predetermined position, mechanism for retaining said devices relatively in inoperative positions, means for relatively positioning said devices to cause the stoppage of the carriage, a latch for holding said devices relatively in stopping positions during return movement of the carriage, a space bar, a bail extending transversely of the machine, means under control of the space bar for operating said bail and a lever actuated by the bail to release the latch upon the actuation of the space bar to space the carriage.

16. In a machine of the class described, a carriage movable in opposite directions across the machine, means for moving the carriage in one direction to letter space, power mechanism for imparting return movements to the carriage, a stopping device for arresting the return movement of the carriage, normally held out of stopping position, means for positioning the stopping device to stop the carriage, mechanism for holding said stopping device in stopping position during return movement of the carriage, a type key lever and means operated upon the manipulation of the type key lever for releasing said holding mechanism.

17. In a record making machine, a carriage movable across the machine in advance and return directions, means for moving the carriage in an advance direction, an escapement mechanism for controlling the advance of the carriage, power operated mechanism for returning the carriage, a device for arresting the return movement of the carriage, means for holding said device out of carriage arresting position, mechanism for locating said arresting device in position to arrest the return movement of the carriage, mechanism for retaining said device in carriage arresting po-

sition, a manipulative member for releasing the carriage from the escapement mechanism and mechanism operated upon the actuation of said member for throwing out said retaining mechanism.

18. In a machine of the class described, a transversely movable carriage, mechanism for moving the carriage in one direction during a record making operation, power mechanism for returning the carriage, means for stopping the return movement of the carriage normally located out of stopping position, mechanism for locating said stopping means in position to stop the return movement of the carriage, means for holding said stopping means in stopping position after being located by said mechanism, a manipulative column tabulator control device and mechanism for releasing said holding means upon the actuation of said device to tabulate the carriage.

19. In a record making machine, a carriage movable in opposite directions across the machine, means for moving the carriage in an advance direction, power operated mechanism for returning the carriage in the opposite direction, a device for arresting the return movement of the carriage, means for holding said device in inoperative position, mechanism for positioning said device to arrest the carriage, retaining means for holding said device in carriage arresting position, a manipulative decimal tabulator control member and means for releasing said retaining means upon the actuation of said member to tabulate the carriage.

20. In a machine of the class described, a transversely movable carriage, mechanism for moving the carriage across the machine in one direction, power mechanism for returning the carriage in the opposite direction, means for arresting the return movement of the carriage, normally held in inoperative position, means for locating said arresting means in position to stop the carriage, retaining mechanism for holding said arresting means in arresting position, a manually controlled spacing device and mechanism controlled by said spacing device for releasing said retaining mechanism upon the actuation of said spacing device to space the carriage.

OSCAR J. SUNDSTRAND.
